Inventor:

John H. Heyser

UNITED STATES PATENT OFFICE.

JOHN H. HEYSER, OF HAGERSTOWN, MARYLAND.

IMPROVEMENT IN WINDMILLS.

Specification forming part of Letters Patent No. 57,131, dated August 14, 1866.

To all whom it may concern:

Be it known that I, JOHN H. HEYSER, of Hagerstown, of Washington county, and State of Maryland, have invented a new and improved mode of regulating the action of the wind on the sails or wheel of a windmill, and also regulating the power; and I do hereby declare that the following is a full and exact description thereof, reference being had to the accompanying drawings, and to the letters of reference marked thereon.

The nature of my invention consists in exposing a sail in such manner that the wind impinging on it will draw the slides over the wheel, thereby preventing the wind from acting on the whole of it, thereby equalizing the motion, the said slides having weights or their equivalents attached to them in such manner as to alter the power of the wheel.

To enable others skilled in the art to make

and use my invention, I will proceed to describe its construction.

a b c d are a sail; *e e* slides. *f f* are weights attached to the slides *e e* by cords *p p*, the slides attached to the sails by the cords *p p* running over pulleys *g g g*. *H H H H* are fulcrums.

When the sail is driven back the slides are drawn over the wheel or mill. The weights can be so arranged as to regulate the power.

What I claim is—

The sail *a b c d*, slides *e e*, cords *p p*, pulleys *g g*, and fulcrums *H H*, in combination with the wind-wheel, all constructed and arranged as specified, and for the purposes substantially as described and set forth.

JOHN H. HEYSER.
